KERF-CUTTING MACHINE

Thomas E. Pray, Chicago, Ill., assignor to Goodman Manufacturing Company, Chicago, Ill., a corporation of Illinois

Application November 22, 1935, Serial No. 51,003

14 Claims. (Cl. 262—28)

This invention relates to improvements in kerf-cutting machines of the track-mounted type adapted to cut a horizontal kerf in the mine wall along the roof or at various intermediate positions between the roof and floor.

Among the objects of my invention are to provide a tilting support for the cutting element whereby the cutter bar may be tilted about a transverse axis disposed rearwardly of its rearward end, together with a novel means for controlling tilting movement of said cutting element and permitting limited yieldable movement of the cutter bar with respect to the tilting mechanism during the cutting operation. Another object of my invention is to provide novel means for vertically adjusting the cutter bar with respect to the ground when in various tilted positions.

My invention may best be understood with reference to the accompanying drawings wherein:

Figure 1 is a side elevation of a mining machine of the track-mounted type illustrating one form in which my invention may be embodied;

Figure 2 is a fragmentary side elevation of the mining machine shown in Figure 1, showing the cutting element tilted in a different position than in Figure 1;

Figure 3 is an enlarged fragmentary side elevation of the machine shown in Figure 1 with certain parts broken away and shown in longitudinal section in order to more clearly illustrate certain details of my invention;

Figure 4 is an enlarged fragmentary plan view of the forward portion of the machine shown in Figure 1, with certain parts broken away and shown in horizontal section in order to illustrate certain details of my invention;

Figure 5 is an enlarged partial fragmentary detail plan view of one side of the forward portion of the machine with parts broken away and in horizontal section in order to show certain details of the tilting mechanism not shown in Figure 4;

Figure 6 is an enlarged partial fragmentary detail plan view of one side of the forward portion of the machine with parts broken away and in horizontal section showing certain details of the tilting mechanism not shown in Figures 4 and 5;

Figure 7 is an enlarged partial fragmentary detail side elevation of a portion of the machine with certain parts broken away and in section in order to illustrate certain other details of

the tilting mechanism not heretofore shown; and

Figure 8 is a fragmentary transverse sectional view taken through the drive for the mechanism for vertically adjusting the cutting element.

In the drawings, my invention is shown as being embodied in a mining machine of the track-mounted type arranged for cutting a horizontal kerf in the mine wall above the ground. Said mining machine includes a track-mounted truck 10 having a turntable 11 mounted thereon adjacent the forward end thereof. Said turntable forms a support for a cutting element, generally indicated by reference character 12, and also forms a means for feeding a cutter bar 13 projecting from said cutting element across the face of the coal.

The cutting element 12 includes a motor 14 having a frame 15 secured thereto and extending forwardly therefrom. Said frame forms a support for the rearward end of said cutter bar and forms a housing and support means for suitable gearing, driven by the motor 14 for vertically adjusting said cutting element with respect to said turntable and driving a cutter chain 16 about said cutter bar.

With reference now in particular to the novel means for supporting said cutting element for vertical adjustment with respect to said turntable and for pivotal movement about a transverse axis, the frame 15 is provided with a pair of oppositely disposed bored bosses 17, 17 extending laterally therefrom intermediate the ends thereof. Each of said bosses is adapted to have a bored trunnion support member 18 mounted therein and extending laterally therefrom. Each of said trunnion support members is held from movement with respect to said frame in a suitable manner and is journaled in a side frame 19 of a cradle 20 in such a manner that said cutting element may be tilted about a transverse axis coaxial with the axis of pivotal connection of said bosses to said cradle. As herein shown, said trunnion support members are in the form of sleeves having openings in the lower outer portions thereof to accommodate suitable drive gearing for driving the adjusting mechanism, a portion of which drive gearing extends through said trunnion support members.

Each side frame 19 extends along the frame 15 and has slidably engagement with longitudinally spaced guide surfaces 21, 21 of a vertically extending guide frame 22 (see Figure 4). The portions of said side frames opposite said guide surfaces are shouldered and the shouldered portions

thereof are adapted to be engaged by suitable inward extensions from racks 23, 23 extending upwardly along and secured to the inner sides of said vertical guide frames adjacent the forward 5 and rearward ends thereof. Thus, said inward extensions from said racks form gibbed guides for guiding said side frame members for vertical movement along said guide frames.

The racks 23, 23 are adapted to be meshed with 10 pinions 24, 24 keyed to opposite ends of parallel-spaced longitudinally extending shafts 25, 25. Said shafts are rotatably supported in said cradles on the hubs of said pinions. Each shaft is also journaled intermediate its ends on opposite sides 15 of a worm gear 27 keyed to said shaft in a housing 28 formed integral with said side frame, the upper portion of which housing forms a bearing support means for the trunnion support members 18, 18. Said worm gears, as herein shown, extend 20 through the open portion of said trunnion support members and are meshed with worms 29, 29 on the outer ends of a transversely extending shaft 30.

The transversely extending shaft 30 is reversely 25 driven from the motor 14 without reversal thereof by means of a helical gear 31 keyed on said transversely extending shaft and driven from a helical pinion 32 mounted on a sleeve 33 coaxial with a longitudinally extending shaft 34. A spur gear 35 is mounted on said sleeve adjacent one of the ends thereof and is meshed with an idler gear 36 which idler gear is meshed with a gear 37 freely mounted on a longitudinally extending shaft 38. A suitable friction clutch 39, herein shown as having 30 oppositely disposed frusto-conical engaging surfaces, is feathered on said shaft for selectively driving the gear 37 from said shaft. A gear 40 is freely mounted on said shaft on the opposite side of the clutch member 39 from the gear 37. Said gear 40 is adapted to be selectively driven from said shaft from the opposite frusto-conical engaging surface of said clutch member. Said last-mentioned gear meshes with and drives a spur gear 41 keyed to the end of the sleeve 33 opposite from the spur gear 35. Thus, the transversely extending shaft 30 may be driven from the shaft 38 in opposite directions without reversal thereof for adjustably moving the cradle 20 and cutting element 12 along the guides 22, 22. Said cradle is held in 45 fixed relation with respect to said guides by means of the worms 29, 29 and worm gears 27, 27 which are of the usual self-locking type.

The longitudinally extending shaft 38, besides 50 forming a means for vertically adjusting the cutting element 12 in the guides 22, 22, also forms a means for driving the cutter chain 16 about the cutter bar 13 through a gear train, generally indicated by reference character 43, and said shaft is driven from the motor 14 by means of a motor pinion 44 meshing with a spur gear 45 keyed to 55 the rearward end of said shaft.

Referring now particularly to the means for 60 tilting the cradle 20 about the axis of the trunnion support members 18, 18 and another of the novel features of my invention, each side frame 65 19 is provided with a forwardly extending outboard support member 46 which, together with the tilting mechanism, forms a means for connecting said side frames together to operate as a unit. Inasmuch as the tilting mechanism connected to each outboard support member is the same, a description of one will suffice for both.

The outboard support member 46 has an equalizing arm 47 pivotally connected thereto intermediate its ends on a pivotal pin 48. One end of

said equalizing arm extends inwardly from said pivotal pin and is provided with a seat 49 for a compression spring 50. The opposite end of said compression spring abuts a seat 51 abutting an under portion of the outboard support member 46. As herein shown, two cap screws 52, 52 extend through the outboard support member 46 and are threaded in the seat 49, and a cap screw 53 extends through the equalizing arm 47 and is threaded in the seat 51. Thus, the equalizing arm 10 47 may be yieldably moved about the axis of the pivotal pin 48 and said arm may form a means for equalizing the loads between said frames and permit a limited amount of weaving movement of the cutter bar during the cutting operation. 15

The means for pivoting said cradle includes a pair of spaced links 54, 54 pivotally connected to opposite sides of the forward end of the equalizing arm 47 on a pivotal pin 55. The lower ends of said links are pivotally connected to pins 56, 56 20 extending laterally from a member 57. Said last mentioned member is slidably movable in aligned guides 58 and 59 formed integral with a frame member 60 secured to and extending outwardly from the frame 15. The member 57 has a shaft 25 61 threaded therein which shaft is journaled at its rearward end in a bearing 62 mounted in the frame member 60, which frame member also forms a housing for said shaft and for suitable mechanism for rotating the same. 30

A bevel pinion 63 is keyed on the shaft 61 adjacent the inner side of the bearing 62 and meshes with a bevel pinion 64 on the inner end of a shaft 65. Said shaft is mounted within the hub of a hand wheel 66 and said hand wheel is in turn 35 rotatably mounted in the support frame 60 so that rotation thereof will rotate said shaft and move the member 57 along the guides 58 and 59. The shafts 61, 61 are connected together to operate as a unit by means of bevel pinions 67, 67 on the 40 outer ends of a transversely extending shaft 69.

Thus, rotation of either of the hand wheels 66, 66 in one direction or another will translationally move the members 57, 57 in the guides 58, 59 and pivot the cutting element 12 about the axis of the 45 trunnion support members 18, 18.

It will be seen that said tilting mechanism is so arranged as to permit a limited amount of weaving movement of said cutting element with respect to the cradle during the cutting operation 50 and besides forming a means for tilting the cutting element, also forms a means for connecting the side frames 19, 19 together to operate as a unit.

While I have herein shown and described one 55 form in which my invention may be embodied, it will be understood that the construction and arrangement of the various parts may be changed or altered without departing from the spirit or scope thereof. Furthermore, I do not wish to be 60 construed as limiting myself to the precise construction illustrated, excepting as it may be limited in the appended claims.

I claim as my invention:

1. In a mining machine, a base, a cutting element 65 including a frame having a cutter bar projecting therefrom, means for supporting said cutting element for vertical adjustable movement with respect to said base including a pair of parallel-spaced vertically extending guides mounted 70 on said base, a cradle slidably guided therein, means for adjustably moving said cradle along said guides, a supporting connection between said cradle and cutting element permitting pivotal movement of said cutting element with respect to 75

- said base about a horizontal transverse axis extending between the ends of said guides, and means disposed forwardly of said guides for pivotally moving said cutting element about said transverse axis.
5. In a mining machine, a base, a cutting element including a frame having a cutter bar projecting therefrom, means for supporting said cutting element for vertical adjustment relative to said base including a pair of parallel-spaced vertically extending guides mounted on said base, a cradle slidably guided therein, means for adjustably moving said cradle along said guides, a supporting connection between said cradle and cutting element permitting pivotal movement of said cutting element with respect to said base about a horizontal transverse axis extending between the ends of said guides, and a linkage connection between said cutting element and the forward end 20 of said cradle for pivotally moving said cutting element about said transverse axis.
6. In a mining machine, a base, a cutting element including a frame having a cutter bar projecting therefrom, means for supporting said cutting element for vertical adjustment relative to said base including a pair of parallel-spaced vertically extending guides mounted on said base, a cradle slidably guided therein, a transverse pivotal supporting connection between said cradle and cutting element permitting pivotal movement of said cutting element with respect to said base about an axis extending between the ends of said guides, means for controlling pivotal movement of said cutting element about said transverse axis, and a drive connection from said motor for vertically moving said cradle along said guides comprising a shaft disposed coaxial with the pivotal axis of said cutting element, a pair of parallel-spaced shafts extending along opposite sides of said cutting element and mounted in said cradle, means on opposite ends of said shaft interengageable with said guides, and drive connections from opposite ends of said transverse shaft to said longitudinally extending shafts.
7. In a mining machine, a base, a cutting element including a frame having a cutter bar disposed rearwardly thereof and a cutter bar projecting forwardly therefrom, a pair of parallel-spaced vertically extending guides mounted on said base, a cradle slidably guided therein, a transverse pivotal connection between said cradle and cutting element permitting pivotal movement of said cutting element with respect to said base about an axis extending between the ends of said guides, means for controlling pivotal movement of said cutting element about said transverse axis, and a drive connection from said motor for vertically moving said cradle along said guides comprising a shaft disposed coaxial with the pivotal axis of said cutting element, a worm on each end of said shaft, a worm gear meshing with each of said worms, said worm gears being journaled in said cradle on shafts extending longitudinally thereof, said shafts having means thereon interengageable with corresponding means on said guides for moving said frame 40 therealong upon rotation of said shafts.
8. In a mining machine, a base, a cutting element having a cutter bar projecting therefrom, a pair of parallel spaced guides extending upwardly from said base, and a cradle for supporting said cutting element for movement along said guides including a pair of parallel spaced side frames, each of said frames having slidable engagement with said guides, and said frames being disposed on each side of and forming a pivotal mounting for said cutting element.
9. In a mining machine, a base, a cutting element having a cutter bar projecting therefrom, a pair of parallel spaced guides extending upwardly from said base, and a cradle for supporting said cutting element for movement along said guides including a pair of parallel spaced side frames, each of said frames having slidable engagement with said guides, and said frames having said cutting element pivotally mounted there-
- 75

between for adjustable movement about a horizontal transverse axis extending between the ends of said guides.

10. In a mining machine, a base, a cutting element having a cutter bar projecting therefrom, a pair of parallel spaced guides extending upwardly from said base, and a cradle for supporting said cutting element for movement along said guides including a pair of parallel spaced side frames, each of said frames having slidable engagement with said guides, interengaging drive connections between said side frames and guides for adjustably moving said cradle and cutting element with respect to said base in a vertical direction, and a transverse pivotal supporting connection between opposite sides of said cutting element and said frames.

11. In a mining machine, a base, a cutting element including a motor and a projecting chain carrying cutter bar, a pair of parallel spaced guides extending upwardly from said base, and a cradle for supporting said cutting element for movement along said guides including a pair of parallel spaced side frames, each of said side frames having slidable engagement with said guides, interengaging drive connections between said side frames and guides for adjustably moving said cradle and cutting element with respect to said base in a vertical direction, a transverse pivotal supporting connection between opposite sides of said cutting element and said frames, and means driven by said motor for actuating said drive connections and vertically moving said cutting element with respect to said base comprising a transverse shaft arranged co-axial with the pivotal axis of said cutting element.

12. In a mining machine, a base, a cutting element having a cutter bar projecting therefrom, a pair of parallel spaced guides extending upwardly from said base, and a cradle for supporting said cutting element for movement along said guides including a pair of parallel spaced side frames, each of said side frames having slidable engagement with said guides, and said frames having said cutting element pivotally mounted therebetween for adjustable movement about a horizontal transverse axis extending between said guides, and means for pivotally adjusting said

cutting element with respect to said side frames including outboard supporting members extending from said frames forwardly of said guides and a linkage connection between said outboard supporting members and cutting element.

13. In a mining machine, a base, a cutting element including a frame having a cutter bar projecting therefrom, means for supporting said cutting element for vertical adjustment relative to said base including a pair of parallel-spaced vertically extending guides, a cradle guided in said guides, said cradle including a pair of side frames, one of said frames being disposed on each side of said cutting element and forming a transverse pivotal support therefor intermediate the ends thereof, and means for connecting said side frames together to operate as a unit, said means including said pivotal support between said cutting element and side frames and also including pivoting mechanism mounted on said cutting element on opposite sides thereof and having operative connection with each of said side frames.

14. In a mining machine, a base, a cutting element including a frame having a cutter bar projecting therefrom, means for supporting said cutting element for vertical adjustment relative to said base including a pair of parallel-spaced vertically extending guides, a cradle guided in said guides, said cradle including a pair of side frames, one of said frames being disposed on each side of said cutting element and forming a transverse pivotal support therefor intermediate the ends thereof, and means for connecting said side frames together to operate as a unit, said means including said pivotal support between said cutting element and side frames and also including pivoting mechanism mounted on said cutting element on opposite sides thereof and having operative connection with each of said side frames, and said pivoting mechanism including a pair of arms pivotally connected to said side frames intermediate their ends and having yieldable engagement with said side frames at one of their ends, permitting yieldable pivotal movement of said cutting element with respect to said side frames.

THOMAS E. PRAY.
